UNITED STATES PATENT OFFICE.

ARTHUR H. KLAHN, OF SAN FRANCISCO, CALIFORNIA.

FLUSHING APPARATUS.

1,383,273.

Specification of Letters Patent. Patented June 28, 1921.

Application filed December 26, 1914, Serial No. 879,093. Renewed February 24, 1919. Serial No. 278,934.

To all whom it may concern:

Be it known that I, ARTHUR H. KLAHN, a citizen of the United States, residing at San Francisco, in the county of San Francisco, State of California, have invented a new and useful Flushing Apparatus, of which the following is a specification in such full and clear terms as will enable those skilled in the art to construct and use the same.

This invention relates to an apparatus for flushing toilets and its object is to provide an air tight tank with the inlet and outlet near the bottom, permanently sealed at the upper end and no connections, fittings, or openings at or near the top which might allow the air which is trapped and compressed in the upper end of the tank to escape. Should the air in the tank escape the tank becomes airbound and the water cannot escape therefrom any faster than it runs in, in which event the float valve will float indefinitely and the water will run out of the tank only as fast as it runs in, the main body of water remaining in the tank.

This apparatus insures a fixed quantity of water for flushing the fixture and automatically discharging the entire contents of the tank at each operation of the lever which lifts the discharge valve.

Another object of the invention is to drain the float valve so as to insure its buoyancy.

Another object of the invention is to provide an air chamber near the check valve on the inlet so that any fluctuation of the water pressure will not allow the check valve to hammer.

Another object of the invention is to provide the regulating valve with means whereby it will be possible to vary its discharge to accommodate it to different water pressures.

Another object of the invention is to provide means whereby the water in the tank cannot be partly drained out of the tank when other fixtures in the house are used.

An embodiment of the invention is shown in the drawing in which the same reference numeral is applied to the same portion throughout, but I am aware that there are many modifications thereof.

Figure 1 is a perspective view of the complete apparatus,

Fig. 2 is a vertical sectional view through the regulating valve, 55

Fig. 3 is a vertical sectional view through the tank and wall,

Figs. 4 and 5 are plan views of two different sized outlet regulating disks,

Fig. 6 is a sectional view through a valve of slightly modified form from that shown in the previous figures, 60

Fig. 7 is a vertical sectional view showing a slightly modified form of tank, and

Fig. 8 is a sectional view showing the 65 valve for preventing the water from passing into the float valve.

The numeral 1 represents a closed tank having the small supply pipe 2 connected with the bottom thereof, over which is the 70 check valve 3, said valve being pivoted on lugs 4 secured to the inside of the bottom of the tank. The tank is made of any suitably heavy material to withstand the pressure of water to be applied thereto and other than 75 the check valve 3 has no movable parts. Connected with the bottom of the tank is the outlet pipe 5 extending into an elbow 6 into which the nipple 7 extends, the other end of said nipple being connected with the inlet 80 pipe 8 of the regulating valve 9.

The regulating valve 9 has an enlarged chamber covered by the dome shaped cap 10 screwed thereto and it is provided with a seat at the bottom for the discharge disk 11 85 and gasket 12. The outlet pipe 13 has a projection 14 thereon which has an opening therein for the operating shaft 15, which shaft has the handle 16 on one end and the operating lever 17 extending into the 90 pipe 13.

The operating lever carries a rod 18 which is pivoted to the lever 17 and an enlargement 19 enables the operating lever to lift the ball float valve 20 by striking the bottom of the tube 21, said tube acting as a guide for the ball valve and also affording the means whereby the ball valve is lifted. The tube has a drain opening 22 into the inside of the ball valve and the tube is long 100 enough so that as the water rushes by the end of the tube that it will not back up into the float valve and as soon as the valve is again seated whatever water may by any accident collect in the ball valve will at once 105 drain out.

The discharge pipe 13 is connected by means of the coupling 23 with a pipe 24 leading to the place of discharge. Different sized outlet disks 25 or 26 may be used as required.

The inlet pipe 8 has a depending lip 27 in which is an opening 28, the object being to prevent the water rushing into the regulating valve from disturbing the float valve and also to allow the water to rise high enough in the regulating valve air chamber to insure against the accidental seating of the valve after it has once opened. The air for the operation of the valve is trapped in the cap 10 and also prevents the water from hammering should the valve prematurely close.

The operation of the apparatus is as follows: Water under pressure passes from the pipe 2 into the tank, whereupon with the ball valve seated, the tank 1 will fill until the air pressure therein is equal to the water pressure. Upon the unseating of the ball valve the air under pressure in the tank 25 will rapidly force all of the water in the tank out through the discharge pipe 24, the rate of escape being determined by the initial pressure and also by the size of the outlet disk. As the water fills the regulating 30 valve up to its air chamber the ball float will rise until the outlet opening is free and as long as any quantity of water may remain in the regulating valve the float will not close, but as soon as the flow of 35 water is reduced to that coming in through the pipe 2, the tendency of the water will be to draw the float down against its seat and as soon as it is seated the pressure will hold it closed until again unseated by the 40 operation of the handle 16.

An advantage of the construction herein outlined lies in the fact that it is not necessary to have a tank as large as the amount of water required for a single flushing, because during the time the water is running out of the tank the water is continually running in from the supply pipe and consequently from one-sixth to a quarter or more escapes out of the regulating valve 50 than the tank actually contains.

It is to be observed that whatever size outlet washer is used for the valve that the opening therein must be so proportioned to the supply pipe opening of the tank and the pressure, that the desired charge of water will be blown out of the tank faster than the supply pipe can replenish the water discharged.

In Figs. 6 and 7 the numeral 31 indicates the concealed tank with which the supply pipe 32 is connected, which pipe carries an air chamber 30 and check valve 33. The outlet pipe 35 has an elbow 36 thereon which elbow has a nipple 37 connected with the inlet 38 of the float valve casing 39.

The valve casing 39 has a projection 44 into which a shaft 45 extends, said shaft having a handle 46 and lever 47 connected thereto. The lever 47 carries a lifter 49 large enough to substantially close the 70 opening in the washer 41, the object being to make certain that the float valve 50 does float to the top of the water in the casing 39 without being reseated by the flow of water should it not be fully lifted. The 75 float has a drain opening 51 and a depending tube 48 with which the lifting lever head 49 contacts. The float seats on a gasket 42.

The valve casing has the cover 40 which 80 forms an air chamber and cushion, and the depending flange 55 has an opening therein the same as in the other form of valve shown. The valve is connected to the discharge pipe 54 by the coupling 53.

The float 50 is prevented from filling because of a light ball 51' which is inserted in the tube 48, said tube having grooves 48' which allow the water to pass down, but should the pressure be inwardly, as is the 90 case when the valve is first unseated, the ball 51' floats and stops the entrance into the ball 50. In the previous form of the invention the long tube 21 prevents the water from passing into the ball float. 95

The object of the air chamber 30 is to prevent the other fixtures in a house from causing the valve 33 to hammer because of the considerable air body in the tank 31.

From the foregoing it will be clear that 100 it is necessary to use the particular combination of different elements shown herein to obtain the results described, but no claim is made to any of said elements separately.

Having thus described my invention what 105 I claim as new and desire to secure by Letters Patent of the United States, is as follows, modifications within the scope of the claims being expressly reserved:

1. In a flushing apparatus, the combination of a closed tank, having an outlet larger than its inlet, both inlet and outlet located near the lower end of the tank, a valve casing on the tank outlet, the outlet of said valve casing smaller than its inlet, a float 115 valve covering the outlet of said valve casing, and means to lift the float valve into the upper part of the valve casing to allow the water to be blown out of the tank.

2. In a flushing apparatus, the combination of a closed tank having an outlet larger than its inlet, a valve casing on the tank outlet, the outlet of said valve casing smaller than its inlet, a float valve covering the outlet of said valve casing, and means to lift 125 the float valve off its seat that it may rise to the upper part of the casing during the discharge of water in the tank.

3. In a flushing apparatus, the combination of a closed tank having an outlet larger 130

than its inlet, a valve casing separate from the tank on the tank outlet, the outlet of said valve casing smaller than its inlet, a float valve normally seated over the outlet of said 5 casing, means to lift the float valve into the upper part of the casing, and means to change the difference in area between the inlet and outlet.

4. In a flushing apparatus, the combination of a closed tank having an outlet larger 10 than its inlet, a valve casing adjacent to the tank on the tank outlet, the outlet of said valve casing smaller than its inlet, a float valve normally seated over the outlet of said 15 casing, means to lift the valve into the upper part of said casing, to allow the water to be blown out of the tank, and a check valve on the tank inlet.

5. In a flushing apparatus, the combination 20 of a closed tank having an outlet larger than its inlet, a valve casing adjacent to the tank on the tank outlet, a float valve normally seated over the outlet of said casing, means to lift the float valve into the upper 25 part of said casing, a depending flange or wall within the valve casing to deflect the flow of the water, and to create an area of

undisturbed water in the upper part of the casing during the discharge of the tank, the said depending flange or wall to have an 30 opening at the top to connect the top of the casing with the outlet of the tank, to prevent the upper part of the casing becoming air bound which would reduce the floating 35 area of the float valve.

6. In a flushing apparatus, the combination of a closed tank having an outlet larger than its inlet, a valve casing adjacent to the tank on the tank outlet, the outlet of said valve casing smaller than its inlet, a float 40 valve normally seated over the outlet of said casing, means to raise the float valve into the upper part of the casing and an air chamber on the tank inlet to prevent the check valve from hammering with every 45 change in the water pressure.

In testimony whereof I have hereunto set my hand this 19th day of December, A. D. 1914, in the presence of the two subscribed witnesses.

ARTHUR H. KLAHN.
